UNITED STATES PATENT OFFICE.

GEORGE W. BURROW, OF NEAR CAMPBELL, CALIFORNIA.

MOTOR.

Application filed May 6, 1926. Serial No. 107,137.

- This invention relates particularly to that type of motors in which the shaft is actuated through the medium of a rotary piston instead of the well-known reciprocating piston.
- 5 It is one object of the invention to provide a motor of the character indicated in which a continuous rotating movement is imparted to the shaft without the use of reciprocating or intermittently moving parts.
- 10 It is another object of the invention to provide a motor of the character indicated wherein the chambers are effectually scavenged after each explosion when the motor is designed as a combustion engine.
- 15 It is also an object of the invention to provide a motor of the character indicated that will develop high power in proportion to its size and weight, that consists of few parts easily assembled and disassembled, economical to manufacture, and highly efficient in its practical application.
- 20 It is also an object of the invention to provide a motor in which there is but little loss of power through friction between moving parts.
- 25 In the drawing:—
- Figure 1 is a side elevation of the motor.
- Figure 2 is a half section on line 2—2 of Figure 1.
- 30 Figure 3 is a sectional view on line 3—3, Figure 2.
- Figure 4 is a sectional view on line 4—4, Figure 1.
- 35 Figure 5 is a detail section showing the rotary piston construction on line 5—5 of Figure 3.
- Figure 6 is a detail of the piston structure on line 6—6 of Figure 5.
- 40 Referring now more particularly to the drawing, I show at 1 an annular casting provided with brackets 2 by means of which it is mounted on any suitable support as 3. This casting 1 is provided with outwardly extending side flanges as 4 and has portions 5 of increased thickness at diametrically opposite points, these thickened parts having guideways 6 formed therein as shown. On either side of one of these portions 5 are formed orifices 7 and 8, shown in Figure 3, the orifice 8 being provided with a connection 9 through which a combustible mixture is introduced from a source of supply (not shown).
- 45 On each side of part 1 is mounted a plate 10 by means of bolts 11 and extending a distance inwardly toward the axis of the part as shown. In one of these plates are formed two ports as 12 and 13. These ports are spaced a distance apart both radially and circumferentially and lie upon opposite sides 60 of a radial plane bisecting the portions 5 and adjacent to the portion 5 opposite the ports 7 and 8.
- 50 Mounted in guideways 6 in one portion 5 and between the ports 12 and 13 are gates 14. 65 The stems 15 of each gate are connected at their outer ends by a bar 16 rigidly mounted on part 1 by a support 17. These stems slide in the said bar and carry collars 18 fixedly mounted thereon, springs 19 being inserted 70 between the collars and the bar as shown whereby to urge the gates inwardly.
- 55 A second set of gates constructed, mounted and operated in the same manner are shown at 14^a, 15^a, 16^a, 17^a, 18^a, and 19^a, diametrically 75 opposite to the above described parts, and located between the ports 7 and 8.
- 60 At 20 is shown a shaft concentrically positioned relative to part 1 and carrying an annular element 21 having cams 22—23 formed 80 on its outer surface and positioned diametrically opposite to each other. The element 21 is somewhat smaller in diameter than the inner circumference of part 1 thereby forming a chamber 24 therebetween, and the cams 85 22—23 are in working contact with the inner circumference of part 1. Since the chamber 24 is rectangular in transverse cross section the peak of each cam is slotted as at 25 to receive overlapping bars 26 and a spring 27 arranged between the bars and the bottom of the slot, the lower edge of the side portions of the slot being bevelled as at 28. By this construction the bars 26 are held in close contact with the wall of part 1 and effectually 90 prevents the passage of any gas therebetween. The sides of the element 21 are recessed to receive plates 10 packing being inserted between the two as at 29.
- 95 At 30 I show a valve plate mounted on one side of element 21 and secured by screws 31 and overlapping plate 10. This plate 30 is provided with offset slots 32—32^a and 33—33^a arranged to operate in conjunction with ports 12 and 13, the pairs of slots being concentrically arranged relative to the axis of shaft 20 as shown and the slots of each pair being arranged diametrically opposite to each other.
- 100 Enclosing each side of the structure described is a face plate 34 secured by the bolts 11, suitable packing being inserted between 105
- 110

the same and plate 30 as shown at 35. In this plate 34 is formed a combustion chamber 36 positioned to communicate with chamber 24 through the ports 12 and 13 when uncovered by the rotating valve plate 30. This chamber 36 is provided with a spark plug 37, the timing mechanism and source of electrical supply not being shown. The water jacket is indicated at 38, and a collar is shown at 39 bolted to plate 34 as at 40.

In this construction there are three main fixed features, namely, the annular part 1, the plates 10, and the plates 34, all tied together by the bolts 11.

15 The rotating parts comprise only the part 21 on shaft 20 and the valve plate 30 mounted on the shaft and secured to part 21.

The operation of the motor is as follows, it being assumed that the same is in full operation with the several parts in the relative positions shown in the drawing. The gates 14—14^a are forced down into contact with the part 21 by springs 19—19^a thereby dividing the chamber 24 into two equal parts. The 25 cams 22—23 have just passed the gates so that the port 12 from the combustion chamber 36 is opened through valve port 32 and between the cam 22 and gates 14, and the intake port 8 is opened into chamber 24 between cam 23 and gates 14^a. The port 13 is closed but the exhaust port 7 is always open.

An explosion occurs in chamber 36 and the expanding gases pass through ports 12—32 into chamber 24 and act upon the cam 22 and 25 force the member 21 and shaft 20 to revolve. The expanding gases flow into chamber 24 as long as the port 32 uncovers port 12 and at the same time the burnt gases in front of cam 22 are forced out through the exhaust 40 port 7 and a fresh charge is being drawn into the chamber between cam 23 and gates 14^a. The fresh charge drawn into chamber 24 by the previous rotation of member 21 and now trapped between cam 23 and gates 14 is now 45 compressed between cam 23 and gates 14 until the rotating plate 30 brings port 33 into registration with the port 13 thereby permitting the compressed charge to flow into the combustion chamber 36. These several parts are 50 so designed that the valve port 33 registers with port 13 a moment before port 12 is closed so that some of the fresh charge will blow completely through the chamber and an efficient scavenging is secured.

55 It is clear from the foregoing description that cam 22, for instance, is acted upon by the expanding gases during the full period of expansion; that it effectually and completely discharges the burnt gases which have acted 60 upon cam 23; that it follows the step of exhausting the burnt gases by inducting a fresh charge into the compression chamber and at the same time compresses a charge and drives it into the explosion chamber. Since the cam 65 23 functions in the same way it follows that

in one complete revolution of shaft 20 two combustible charges have been inducted into chamber 24, exploded, and discharged therefrom.

It is to be understood, of course, that while I have herein shown and described but one specific embodiment of the invention changes in form, construction, and method of operation may be made within the scope of the appended claims.

I claim:—

1. A rotary motor comprising an annular chamber, a revoluble shaft concentrically mounted therein, an annular member of less diameter than said chamber mounted on said shaft to revolve in said chamber and having cam surfaces formed thereon in diametrically opposite relation to each other and extending outwardly to engage the wall of said chamber, radially arranged gate members resiliently mounted in opposed relation to each other on diametrically opposite sides of said chamber and engaging the periphery of said cam member, a combustion chamber, ports connecting said chambers on either side of said gate members, and a rotary valve plate carried by said shaft and adapted to open and close said ports at given intervals in its revolution.

2. A rotary motor comprising an annular chamber having side walls extending inwardly a distance toward its axis, a shaft concentrically mounted therein, an annular member of less diameter than said chamber mounted on said shaft to revolve in said chamber and overlapping said side walls and having cam surfaces formed on its perimeter and extending outwardly to engage the wall of said chamber, a valve plate mounted to rotate as a unit with said shaft and annular member and overlapping said side wall of the chamber in opposed relation to said annular member, a combustion chamber mounted in operative relation to the valve plate, the wall of said first mentioned chamber having ports formed therein in operative relation to said combustion chamber, and gate members resiliently mounted in said first mentioned chamber between said ports and engaging said annular member.

3. A rotary motor comprising a stator having an annular chamber formed therein, a rotary piston operatively mounted in said chamber, means positioned on diametrically opposite sides of the chamber wall for maintaining constant sliding engagement with the rotor, means positioned on diametrically opposite sides of the rotor for maintaining constant sliding engagement with the chamber wall, a combustion chamber having ports connecting with said first chamber on either side of one of said first mentioned means, intake and exhaust ports positioned on either side of the other of said first mentioned means, and an apertured plate mounted as an

integral part of said rotor and extending outwardly therefrom to effect intermittent registration of the apertures therein with said combustion chamber ports.

- 5 4. A rotary motor comprising a stator having an annular chamber formed therein, a rotary piston operatively mounted in said chamber, means positioned on diametrically opposite sides of the chamber wall for maintaining constant sliding engagement with the rotor, means positioned on diametrically opposite sides of the rotor for maintaining constant sliding engagement with the chamber wall, a combustion chamber having ports 10 connecting with said first chamber on either side of one of said first mentioned means, intake and exhaust ports positioned on either side of the other of said first mentioned means, and a plate mounted as an integral 15 part of said rotor and extending outwardly therefrom to overlie the said ports in the combustion chamber and having spaced slots adapted to register alternately with one of said last mentioned ports and other spaced 20 slots adapted to register alternately with the other of said last mentioned ports.
- 25 5. A rotary motor comprising a shaft having a rotary piston and an annular apertured plate mounted thereon, a casing enclosing said piston and plate to form a chamber between the piston and casing, means positioned on diametrically opposite sides of the chamber wall for maintaining constant sliding engagement with the piston, means positioned on diametrically opposite sides of the piston for maintaining constant sliding engagement with the chamber wall, a combus- 30 35

tion chamber having ports connecting with said first chamber on either side of one of said first mentioned means, intake and exhaust ports positioned on either side of the other of said first mentioned means, the said apertured plate extending into the combustion chamber and having ports formed therein registrable with said first mentioned ports. 40 45

5. The structure set forth in claim 3 in which the combustion chamber ports are offset both radially and circumferentially.

7. A rotary motor comprising a casing having an annular chamber formed therein and inlet and exhaust ports communicating with the chamber, a shaft having a rotor thereon concentrically mounted in the chamber, means positioned on diametrically opposite sides of the chamber wall for maintaining constant sliding engagement with the rotor, means positioned on diametrically opposite sides of the rotor for maintaining constant sliding engagement with the chamber wall, a plate mounted on the side of said casing and extending inwardly a distance toward said shaft and having a pair of circumferentially and radially spaced ports formed therein and overlying the side of the said rotor, a combustion chamber mounted upon the outer side of said plate, and an annular plate mounted to rotate with the rotor and extending outwardly a distance to overlie said first plate and pass through the combustion chamber and having ports formed therein registrable with the ports in said first plate. 50 55 60 65 70
